SKIRT HANGER

Kenneth R. Paul, Corvallis, Oreg.

Application August 8, 1955, Serial No. 526,953

8 Claims. (Cl. 223—88)

This invention relates to improvements in garment supporting means, and more specifically relates to devices for hanging skirts and similar articles of wearing apparel.

A principal object of the present invention is to provide skirt supporting means which is simple in structure and inexpensive to manufacture and which is efficient for holding skirts thereon without injuring or creasing said skirt.

It is also an object of the present invention to provide skirt supporting attachment means which utilizes a conventional wire-type coat hanger as the frame structure therefor.

A still further object is to provide skirt supporting means having improved spring operated slide means adapted to move in relative horizontal directions for engaging said skirt.

Another object is to provide a garment hanger having improved adjustment means for varying the lateral reach of said hanger.

The above described objects are accomplished by an assembly comprising, briefly, a pair of slide members and a pair of caps arranged removably to be mounted on a conventional wire-type coat hanger. The slide members are urged toward opposite ends of the hanger by spring means and have garment engaging members thereon for frictionally supporting a garment. The garment engaging members have longitudinally adjustable means for varying the lateral reach of the device wherein different size garments may be held thereon.

The invention will be better understood and additional objects and advantages will become apparent from the following description taken in connection with the accompanying drawings which illustrate preferred forms of the invention. It is to be understood, however, that the invention may take still other forms and that all such modifications and variations within the scope of the appended claims which will occur to persons skilled in the art are included in the invention.

In the drawings:

Figure 1 is a perspective view of a conventional wire-type coat hanger with the present skirt engaging attachment thereon;

Figure 2 is a sectional view taken on the line 2—2 of Figure 1 and showing in particular the garment engaging members and means for varying the effective lateral reach of the hanger;

Figure 3 is a sectional view taken on the line 3—3 of Figure 1, showing the cap structure which engages end portions of a conventional hanger;

Figure 4 is an elevational view of a portion of the cap structure;

Figure 5 is a sectional view taken on the line 5—5 of Figure 1;

Figure 6 is a sectional view taken on the line 6—6 of Figure 1;

Figure 7 is an elevational view of a modified form of cap structure;

Figure 8 is a sectional view taken on the line 8—8 of Figure 7; and

2

Figure 9 is a sectional view showing a modified form of slide member.

Referring to the drawings and more specifically to Figure 1, the numeral 10 refers generally to a conventional wire-type coat hanger having a hook 11, laterally extending sloping shoulder bars 12, and a horizontal bar 13. This type of hanger is used for supporting articles of clothing such as coats, blouses, shirts, trousers, and the like, but by itself is not satisfactory for supporting skirts and like garments because such garments must in some way be positively gripped to be held thereon.

A preferred form of the present invention is shown in Figures 1—6 and is adapted to be applied to the type of hanger described. The invention comprises, in general, a pair of caps 14 and a pair of slide members 15 and 16. The caps 14 are D-shaped and have a central slot or recess 17 forming opposite side walls 18 and 19. The recess 17 of each cap is shaped so as to conform substantially to the contour of the end portions of the coat hanger 10 and the caps are mounted on the hanger by engagement of said end portions in the recesses. The caps 14 are positively secured in place by means of inserts 20, Figure 4, which fit in the recesses 17 after the cap is in place and abut the inner radius of curvature of the end portions of the hanger, the inserts 20 each having an apertured ear 20a thereon. The caps 14 and the inserts 20 are apertured at 21 and 22, respectively, to receive transverse pins 23 which hold the inserts in place relative to the caps and insure a positive engagement between the caps and the hanger. If desired, however, the insert 20 may be omitted because the caps will generally be held in place by other mechanism of the attachment to be described.

Each of the slides 15 and 16 has an upper longitudinal enlargement 24 provided with a central bore 25 to form a tubular or sleeve portion for slidably mounting the slides on the horizontal bar portion 13 of the hanger. A longitudinal slot 26 is provided in one side of the sleeve portions 24 and provides an opening for readily attaching said slide to the coat hanger by moving the horizontal bar portion 13 through the slot 26. The bores 25 of the sleeves are slightly larger than the bar portion 13 of the hanger so that the slides will move freely longitudinally thereof, and the slots 26 are preferably slightly narrower than the diameter of the bar 13 so that the slides must be forced into engagement with the bar and, therefore, will not be accidentally displaced therefrom when once applied on the hanger.

Slides 15 and 16 have bottom longitudinal enlargements or guide portions 29 and 30, respectively, each having a central bore 31 open at the outer end and closed at the inner end. The interior walls of bores 31 in each enlargement 29 and 30 are provided with top and bottom grooves 32 and 33, respectively, and as will be seen in Figure 2, the groove 32 in the slide 15 extends the full length of the bore 31 and the groove 33 extends approximately half the length of bore 31. In the slide 16 the top groove 32 extends approximately half the length of bore 31 and the bottom groove 33 extends the full length. Slidably mounted in the bores 31 of the slides 15 and 16 are plungers or pusher rods 35 and 36, respectively, each provided with a head portion 37 having a pair of flanges 38 and 39. The plunger 35 is provided with a full length top tongue or ridge 40 and the plunger 36 is provided with a full length bottom tongue or ridge 41.

The tongue structure on the plungers 35 and 36 and the groove arrangement in the interior of bottom enlargements 29 and 30 accomplish adjustment of the reach of the hanger so that skirts of different sizes may be mounted thereon. To illustrate, when the plunger 35 is mounted in the bore 31 of the left slide 15, as shown in the drawings, the tongue 40 engages the full length top

groove 32 and the plunger is thereby permitted to move the full length of the bore 31. As the plunger 36 has its tongue 41 on the bottom side thereof and the bottom groove 33 extends the full length of the bore 31 in the slide 16, the plunger 36 can likewise move the full length of the bore 31 in said slide. When it is desired to adjust the reach of the skirt hanger, however, the two plungers are interchanged to the opposite slide members, as shown in dotted lines in Figure 2. Therefore, with the plunger 35 in the slide 16, the tongue 40 engages in the short groove 32 and the inward movement of the plunger is limited by engagement of the tongue 40 with the end wall of the groove 32 to hold the plunger in extended position. Similarly, when the plunger 36 is mounted in the slide 15, the full length bottom tongue 41 engages in short groove 33 and holds the plunger 36 in extended position. The lateral reach of the hanger may thus be adjusted for skirts of different waist sizes.

Slides 15 and 16 are provided with upstanding finger grips 45 and are biased toward the ends of the hanger by springs 46 connected between the finger grips 45 and the ears 20a on the inserts 20.

To mount a skirt on the present device, the skirt band is buttoned or zipped, as the case may be, and is placed over the two oppositely directed plungers, the slides 15 and 16 being drawn together toward the center of the hanger a sufficient amount by manual engagement of finger tabs 45 so that the plungers engage the inner portion of the waist band. When the slides are released, the springs bias the plungers outwardly to engage the skirt band and support the skirt. The flange 38 on the head 37 of each plunger projects over the top edge of the skirt band so that the skirt cannot slip upwardly relative to the head and be released therefrom. The flange 39 establishes a frictional engagement with the skirt band to prevent accidental displacement of the skirt from the hanger.

Figures 7 and 8 show a modified form of cap 14' which is formed from a pair of mating halves 50 and 51 provided with opposed recesses 52 in the abutting surfaces. Recesses 52 assume a contour similar to the end portion of a coat hanger whereby the two halves 50 and 51 are adapted to be clamped on a coat hanger by means of a screw 53.

Figure 9 shows a modified form of slide member 55 utilizing an integral rod or arm portion 56 provided with a head 37'. Similar to the preferred embodiment, head 37' has a top flange 38' for preventing a skirt from accidentally moving upwardly relative to the head and has a friction flange 39' to insure a positive grip on the skirt.

The present device may be inexpensively made from plastic or other material and may be made available to customers in kits which may be readily applied to a conventional wire-type coat hanger. The assembled device is readily manipulated by one hand whereby the skirt can be mounted thereon by the opposite hand. The skirt is removed simply by pulling it downwardly out of frictional engagement with the heads 37.

Having now described my invention and in what manner the same may be used, what I claim as new and desire to protect by Letters Patent is:

1. An attachment for a garment hanger of the type having a horizontal supporting bar, comprising a pair of tubular members adapted to be slidably mounted on said bar, said tubular members having full length slots through the walls thereof for removably mounting said members on said bar, biasing means engageable with said members for urging said members in opposite directions, and means on said members for frictionally engaging a garment to be supported thereby.

2. An attachment for a garment hanger of the type having a horizontal supporting bar terminating in upwardly turned end portions, comprising a pair of slides adapted to be mounted on said bar, cap members adapted to be clamped on said end portions, biasing means con-

nected between said cap members and said slides for urging said slides toward said cap members, and head means on said slides for frictionally engaging a garment to be supported thereby.

3. A garment hanger comprising a supporting bar, a pair of slide members movable on said bar, said slide members being biased in opposite directions and having longitudinal guide portions suspended below said bar, rods slidably in said guide portions, and means on said rods for engaging a garment to be carried thereon.

4. A garment hanger comprising a supporting bar, a pair of members having a first longitudinal bore slidably receiving said bar, said members having full length longitudinal slots through the walls thereof communicating with said bores for removably mounting said slides on said bar, and biasing means arranged to urge said members in opposite directions, said members having a second longitudinal bore slidably receiving therein rod portions engageable with the garment to be carried by said hanger.

5. A garment hanger comprising a supporting bar, a pair of members having a first longitudinal bore slidably receiving said bar, said members having full length longitudinal slots through the walls thereof communicating with said bores for removably mounting said slides on said bar, and biasing means arranged to urge said members in opposite directions, said members having a second longitudinal bore disposed below said bore and slidably receiving therein rods engageable with the garment to be carried by said hanger, said rods having adjustable engagement in said second bores for varying the lateral reach of said hanger.

6. An attachment for a wire-type coat hanger having a horizontal supporting bar, comprising a pair of members adapted to be slidably mounted on said bar, tubular guide portions on said members each having internal grooves of different length, rods slidably mounted in said guide portions and having projecting portions arranged to engage a garment, and tongues on said rods engageable in said grooves, said rods being interchangeable in said guide portions wherein in said interchanged positions said rods project a different distance from said guide portions.

7. An attachment for a wire-type coat hanger of the type having a horizontal supporting bar, comprising a pair of members adapted to be slidably mounted on said bar, a pair of tubular guide portions on said members, rods slidably mounted in said guide portions and projecting from one end thereof to provide a lateral reach for said hanger for supporting skirts and the like, said tubular guide portions each having a pair of internal longitudinal grooves, each of said grooves in a pair being of different length, and abutment guide members on said rods engageable in said grooves, said rods being interchangeable in said guide portions wherein in interchanged positions said rods project a different distance out of said guide portions.

8. An attachment for a garment hanger of the type having a horizontal supporting bar terminating in turned end portions, comprising a pair of slides adapted to be mounted on said bar, cap members adapted to be clamped on said end portions, said cap members having an interior opening with confining walls thereof assuming the contour of said end portions wherein said cap members fit snugly on said hanger in clamped position, biasing means connected between said cap members and said slides for urging said slides toward said cap members, and head means on said slides for frictionally engaging a garment to be supported thereby.
